UNITED STATES PATENT OFFICE.

EMIL LADEWIG, OF VIENNA, AUSTRIA, ASSIGNOR TO BÖHMISCH MÄHRISCHE MALZ-FABRIK AND EXPORT GESELLSCHAFT KLATSCHER AND LORENZ, OF PRAGUE, CZECHOSLOVAKIA.

SET OF TOY INTERFITTING BUILDING BLOCKS.

Application filed October 29, 1923, Serial No. 671,557, and in Austria November 14, 1922.

This invention relates to sets of toy interfitting building blocks comprising blocks or figures or groups of blocks or figures, such as for instance houses, furniture, and the like, which are adapted to be set up singly or separately, and the invention has for its object to provide an improved set wherein the box for containing these blocks or figures (hereinafter termed "blocks") is itself constituted by the assemblage of a plurality (consisting of a part of the totality of the set of blocks) which when properly fitted together, will constitute a structure that is not liable to fall to pieces readily.

For this object blocks or groups of blocks made in one piece are united in pairs, and engaged with one another so that to form plates which then constitute the walls of the box for the reception of the residual blocks of the set, and have such dimensions that the internal capacity of the box is able to contain just the whole of the said residual blocks when these have been suitably fitted together. Preferably the blocks designed to constitute the box are made of angle shape, whereby not only the rigidity or firmness of the "stance" of the individual blocks, but also the fitting together of the box is facilitated.

An effective rigidity of the assembled walls of the box is attained when two pairs of angle shaped wall-blocks are provided of which the pair which is united to form a rectangular frame encloses the other pair in the transverse direction, and thus constitutes a completely closed chamber adapted to receive the other blocks.

A constructional form of an improved toy building block set according to this invention is illustrated by way of example in the accompanying drawings in which:

Figure 1 is a perspective view of a box adapted to be formed by means of angle pieces designed to constitute groups of blocks assembled together, the box being shown drawn apart in both the vertical and horizontal directions.

Figure 2 shows the angle pieces of the outer shell, the rear pair of blocks being shown fitted together, whilst the upper block has been removed from the lower block of the front pair.

Figure 3 shows the box completely closed. Figure 4 shows the box in a half finished

state, at the back the outer pair of angle plates is shown upright and inside the same, the inner lower pair of angle plates is shown horizontal; the other blocks which are intended to fill the interior of the box, are shown in course of building upon the said inner lower pair.

The illustrated example consists of a plurality of blocks representing houses and rows of houses which are suitably painted, or subdivided by lines not shown. The zig-zag gabled roofs *a* of two rows of houses which are united together to constitute a single plate portion *A*, are cut from a rectangular plate, preferably of angle shape, in such a manner that the two parts with the roof surfaces fit exactly in one another. The joints may be produced by sawing through or cutting a single plate, or they may be produced separately from separate plates. The two pairs of angle plates constitute a rectangular frame. In order to close the interior of the box on all sides, there is provided a second pair of angle plates *B* which (like the plates *A*) are composed of pairs of mutually supplementing blocks, but so dimensioned that the frame formed by *B* *B'* is adapted when fitted around the frame formed by *A* *A'* to constitute a cube-like body closed on all sides, (Fig. 3). The residual blocks or groups of blocks *b* *c* etc., are fitted into the interior of the box which is partly opened (Fig. 4), and these blocks or groups of blocks are so designed as regards numbers and shapes that when they are suitably fitted together they will fill completely the interior of the box. Since this operation requires certain amount of practice, it will have the character of a cubical puzzle game.

In setting up the blocks the longitudinal groups of blocks that constitutes the box plates, serve for the construction of streets or open spaces, whereas, the blocks contained in the interior of the box are adapted to form short rows of houses or single buildings to be erected upon the open spaces bounded by them.

The parts of the box may be provided with tongues or fillets *d*, projections, etc., which must however not hinder the assemblage of the blocks to form the box.

In order to prevent the parts of the box from falling apart unobtrusive fastenings

such as for instance press-studs, fishplates or the like (not shown), may be provided.

What I claim is:—

1. A toy comprising a pair of angular members, each of said members being provided with one irregular edge, said irregular edges being adapted to fully contact and interfit when brought together, and a second pair of angular members, each of which is provided with one irregular edge, the irregular edges of said second pair of members also being adapted to fully contact and interfit when brought together, the legs of said first and second pairs of members being dimensioned to form a rectangular frame when the ends of the legs of the first

pair of members abut the ends of the legs of the second pair of members.

2. A toy as claimed in claim 1 including third and fourth pairs of angular members arranged within the first and second pairs of members, each of the members of said third and fourth pairs having an irregular edge adapted to fully contact and interfit with another of said members, said third and fourth pairs of members being further adapted to form a rectangular frame, whereby the four pairs of members in assembled relation constitute a closed hollow box.

In testimony whereof I have signed my name to this specification.

EMIL LADEWIG.
